UNITED STATES PATENT OFFICE.

PERRY J. EKSTRAND AND LESLIE E. WATERMAN, OF WEST SUPERIOR,
WISCONSIN.

COMBINED HOT-WATER HEATER AND COOKING-RANGE.

SPECIFICATION forming part of Letters Patent No. 550,677, dated December 3, 1895.

Application filed March 17, 1894. Serial No. 504,090. (No model.)

To all whom it may concern:

Be it known that we, PERRY J. EKSTRAND and LESLIE E. WATERMAN, citizens of the United States, residing at West Superior, in the county of Douglas and State of Wisconsin, have invented certain new and useful Improvements in a Combined Hot-Water Heater and Cooking-Range; and we do hereby declare the following to be a full, clear, and exact description of the invention, which will enable others skilled in the art to which it appertains to make and use the same.

Our invention relates to an improved combined hot-water heater and cooking-range; and the invention consists in employing a hot-water heater in connection with or as a conjunction to a cooking-range, by means of which water may be kept hot for the purpose of warming houses and without interfering in any way with the operation of the range.

The objects of the invention are to provide and produce a hot-water heater in connection with a cooking-range which will be of simple construction and which can be effectively used for any desired purpose.

For a better comprehension of our invention attention is directed to the accompanying drawings, forming a part of this specification, in which—

30 Figure 1 is a front elevation, partly in section, of our invention, showing the hot-water heater in connection with the range; Fig. 2, a longitudinal sectional view taken on the line $\alpha\alpha$ of Fig. 1, and Fig. 3 a top view of the fire-box of the hot-water heater.

35 In all of the above views corresponding parts are designated by the same letters of reference.

40 A is a cooking-range, of any approved construction, provided with a fire-box B, stack C, and flue D from the fire-box to the stack. The said range is also provided with the usual ovens, doors, and pot-holes in the top thereof. At one side of the stove A is a rectangular 45 metallic casing E, constituting the covering for my improved hot-water heater. This casing E is preferably attached to the stove in any suitable way, such as by the angle-iron a and tie-plates b; but the said casing may be 50 a permanent part of the stove and incapable of being removed therefrom.

F is the fire-box within the hot-water heater and is arranged some distance from the bottom thereof. This fire-box is made, preferably, of a hollow casting of the general rectangular shape shown in Fig. 3 and with inclined inner edges c. At the bottom of the fire-box F are the grate-bars d, of any approved construction, and beneath said fire-box is the ash-pit G.

55 H is a rectangular drum vertically mounted with the hot-water heater extending from the front to the back thereof, by which means the said drum will be supported. Extending out from the said drum over the fire-box F are 60 the pipes e, arranged in pairs and connected by the double elbows f, the said pipes e being arranged as closely together as possible, so that the full effects of the heat from the fireplace F will be obtained. Extending out 65 from the drum H, on the other side thereof, are the single pipes g, arranged substantially like the tubes of a porcupine boiler, each tube being provided on its end with a cap h, which may be removed and the pipes cleaned when 70 desired.

75 Water is admitted into the hollow fire-box F by means of a pipe i and is circulated out of the drum H by means of a pipe j. The fire-box F is connected to said drum by means 80 of a pipe k. The hot water is circulated out of the drum H and passes through any desired hot-water radiator or radiators appropriately arranged in the house and returns to the heating apparatus by the pipe i. A 85 short distance below the drum H, in line therewith and resting preferably on the fire-box F, is a small rectangular drum I, which extends from the front to the back of the hot-water heater. Pipes L L extend from the 90 said drums I and convey heated water therefrom to the hot-water spigots of the house.

95 It will be observed that the small drum I is arranged immediately between and supports the fireplaces B and F of the range and heater, respectively, so that the water in the drum I will be heated by the fire in either of said fireplaces. The space between the drums H and I constitute a flue m, provided with a damper n therein, which can be closed when 100 desired, and the space above the drum H constitutes a flue o, through which the products

of combustion may pass through the fireplace F. In the top of the casing E of the hot-water heater are pot-holes p, of any suitable size and number and arranged in any desired way, 5 for the usual purposes of cooking, &c.

The operation of our improved device will be readily understood. In summer, when it is not desired to utilize the hot-water heater, the fire is built in the fireplace B, and the 10 range operates in the usual way, the heat from the fire intending to heat the drum I, so that the water therein will always be kept hot for use for culinary and sanitary purposes. In winter, however, it becomes necessary to 15 make use of the hot-water heater, and the fire is built in the fireplace F, which is purposely larger than the fireplace B, in order that the additional heat required may be generated. The heat of the fire in the fireplace F will di- 20 rectly heat the hollow fire-box constituting such fireplace, and the products of combustion, passing up between and around the pipes e and against the drum II and through and around the pipes g, will heat all of these ele- 25 ments and the water therein. The products of combustion from the fireplace F, passing through the flue at the top of the drum H and down on the other side of the drum H, will pass out through the flue d or through the 30 range A in any suitable and desirable way. If it becomes necessary to lower the heat in the radiators, the damper n is opened and the products of combustion from the fire in the fireplace F will pass directly through the flue 35 m and out of the stack c. It is obvious that a damper may be placed in the flue o; but it

is not thought that this is necessary, since when the damper n is opened a large percentage of the heat will pass out through the flue m. It will also be obvious that by mounting 40 a drum I between the fireplaces B and F the said drum will be heated by either fire, and hot water can always be obtained therefrom for any purpose desired.

Having now described our invention, what 45 we claim as new therein, and desire to secure by Letters Patent, is as follows:

The combination with a cooking range, of a hot water heater attached to or forming part of the same, comprising a hollow fire box F 50 which is mounted to one side of the fire box of the range; a drum I mounted between said fire boxes; pipes L, L, leading to and from said drum I, for the purpose mentioned; a drum II mounted above the drum I with a 55 passage m between said drums; a damper n for said passage; circulating pipes connected with said drum H and mounted in the path of the products of combustion from the fire box F; a circulating pipe i leading into said fire 60 box F; a pipe k connecting said fire box F with the circulating pipes of the drum H; a pipe j leading from said drum H; and a stack common to the fire box of the range and the fire box F, substantially as set forth. 65

In testimony whereof we affix our signatures in presence of two witnesses.

PERRY J. EKSTRAND.
LESLIE E. WATERMAN.
